COUCH BED

Frank Hoffman, Dorchester, Mass., assignor to
New England Bedding Company, Medford,
Mass., a corporation of Massachusetts

Application September 25, 1937, Serial No. 165,721

3 Claims. (Cl. 5—18)

This invention relates to couch beds of the extensible type and its principal objects are to provide a couch bed having back and arm rests, a stationary section, and a movable section which may be automatically extended by manipulation of the arm rests to form a double bed accessible from either side without removing the back rest or any of the parts, and to provide a couch bed which is of simple construction, having but few parts, which is efficient in operation and durable in use, and which can be manufactured and sold at a relatively low cost.

Further objects relate to various features of construction and will be apparent from a consideration of the following description and accompanying drawings, wherein:

Fig. 1 is a front elevation of a couch bed constructed in accordance with the present invention;

Fig. 2 is an enlarged end elevation showing the sections in nested position;

Fig. 3 is an end elevation showing the movable section in extended position; and

Fig. 4 is a fragmentary section on the line 4—4 of Fig. 2.

The particular embodiment chosen for the purpose of illustration comprises a main or movable section and a stationary section, designated generally by the numerals 1 and 2, respectively (Fig. 3), both of which sections may be of conventional construction. The main section 1 comprises a box-like structure having a front wall 4 and side walls 5 and 6, the rear wall being open so that the main section may be moved from about the stationary section. The top of the main section may be of the usual construction for supporting a pair of mattresses 9 which provide the seat cushion when the structure is used as a couch. The outer faces of the front and side walls may be provided with a suitable finish, such as textile fabric which may be secured to the lower mattress so as to hold it in position and give the appearance of continuity therewith. The ends of the side wall are provided with the usual vertically extending angle irons whose lower ends are provided with casters or rollers 11 which support the main section for movement to and from nested position.

The stationary section 2 may be of conventional construction, having longitudinally and transversely extending frame members 14 and 15 which carry the usual spring supporting structure and which are connected to legs or uprights 16. If desired, resilient guards 20 (Fig. 4) may be provided on the inner face of the side walls 5 and

6 to prevent the transverse members 15 from binding against the side walls when the two sections are being moved to and from extended position.

The side walls 5 and 6 of the main section are formed with centrally disposed, vertically extending recesses or channels 22 (Fig. 4) and upstanding brackets 23 are firmly secured within the channels 22. The upper ends of the brackets extend to about the top of the section and are provided with openings which receive pivot pins 24 for supporting a combination back and arm rest, designated generally by the numeral 25 (Fig. 2). As here shown, the back and arm rest consists of a U-shaped member 26 whose lower ends 15 are bent to provide U-shaped members or side rails 27 which constitute the arm rests. Intermediate L-shaped members 28 are integrally joined at their ends to the back and side rails and to the pivot pins 24 adjacent to their bent portions, and a bar 29 is integrally joined at its ends to the legs of the member 26. If desired, the members 26 and 29, constituting a back rest and the members 27 and 28, constituting the sides and arm rests, may be chromium plated, enameled, or otherwise finished to enhance their appearance.

Laterally projecting lugs or angle irons 32 are secured to the side walls 5 and 6 intermediate the brackets 23 and the rear of the section, these lugs being positioned to support the back rest in upright position when the structure is used as a couch. The back rest, arm rests and associated parts are so constructed and arranged that when the arm rests are rotated about the pivot pins 24, the back rest is carried over the seat structure to a position contiguous to the front wall 4, as shown in Fig. 3, thus affording an unobstructed access to the movable section when used either as a section of a double bed or as one of a pair of twin beds.

In order to effect automatic movement of the sections from nested to extended position and back to nested position, I provide links which are constructed and arranged so as to cause the outer section to be pushed outwardly and pulled inwardly in response to rotation of the arm rests or members 27 in one direction or another. As here shown by way of illustration, the arrangement comprises a substantially L-shaped link 35 pivoted at 36 to the depending or vertical part of each arm rest 27, the lower end of the link being pivotally secured at 38 to the front end of a second link or supporting member 40 whose rear end is bent inwardly, as shown in Fig. 4, and

detachably secured to the inner section 2 by a pin and slot connection, indicated at 42.

The design of the link 35 and member 40 is such that when the sections are in nested position (Fig. 2) these parts are normally held in a position coinciding with the vertical and lower horizontal members of the arm rest by an inwardly extending lug 44, integral with the link 35, which engages the vertical member and prevents upward flexing movement of the member 40 and a corresponding inward movement of the link 35; and when the side arms are rotated through an angle of 180° the member 35 acts against the link 40 to cause the outer section to be pushed to fully extended position, as shown in Fig. 3.

When used as a couch the mattresses 9 provide the seat cushion, and pillows may be arranged against the back rest in the usual manner, it being noted that the bars 28 and 29 are positioned to retain the cushions and pillows in place. When the structure is to be used as a double bed or to provide twin beds, the main or movable section may be easily extended by grasping one of the arm rests and rotating it through an angle of 180°. However, it may be necessary merely to rotate the arm rest through an angle of 90° to 120°, thereby to bring the back rest past dead center, in which position the back rest may then be permitted to drop down to the position alongside of the front wall, as shown in Fig. 3, the weight of the back rest being effective to cause continued rotation of the arm rests, which automatically effects outward movement of the main section. When the sections are in extended position, the top mattress 9 may be transferred to the stationary section, thereby providing a double bed, and, if desired, twin beds may be formed by detaching the ends of the links 40 from the inner section. To move the sections back to nested position, it merely is necessary to rotate the arm rests in the opposite direction, such movement being effective to cause the outer section to be pulled inwardly about the inner section.

It will be noted that due to the automatic movement of the outer section in response to rotation of the arm rests, it is necessary that the user take a position at either end of the couch when rotating the arm rests to effect the extension of the sections, since any attempt to rotate the arm rests by reaching over and grasping the back rest 26 would result in the outer section immediately moving outwardly and, striking against the legs of the user, would not only arrest further outward movement, but would also be apt to sweep the user off his feet. It will be further noted that when the structure is in extended position, the back rest proper is disposed well below the level of the mattress on the movable section, and hence does not constitute the slightest obstruction to the movable section.

While I have shown and described one desirable embodiment of the invention, it should be understood that this disclosure is for the purpose of illustration and that various changes in shape, proportion, and arrangement of parts, as well as the substitution of equivalent elements for those herein shown and described, may be made without departing from the spirit and scope of the invention as set forth in the appended claims.

I claim:

1. A couch bed of the class described, comprising a stationary section, a box-like main section having a front, top and side walls enclosing said stationary section when in nested relation therewith, an upstanding bracket secured to each of the side walls of said main section, an arm rest pivotally secured to each bracket, each arm rest having substantially horizontal and vertically extending parts, and actuating means for moving said main section to extended position in response to rotation of the arm rests, said means comprising supporting members secured to the rear end of said stationary section and extending forwardly along the side walls of said main section, and links secured to the front ends of the supporting members and to the vertically extending parts of the arm rests.

2. An extensible studio couch comprising a stationary bed and an overlying movable bed, means holding said beds against separation, including a back rest pivotally mounted on the movable bed and mechanism connecting the two beds and operatively connected to the back rest and operable by said back rest to move the movable bed with respect to the stationary bed to provide a larger sleeping surface, said back rest being pivotally mounted so as to turn about an axis disposed above the plane of the top of the stationary bed and movable to a position to rest on the floor adjacent the front of the movable bed, said back rest, when in the rearward position, holding said beds against separation and serving also as means for moving the movable bed forwardly.

3. In a horizontally extensible couch including an outer bed section and an inner bed section mounted to move rectilinearly relatively to each other into and out of telescoping relation, operative means to move said sections into and out of such telescoping relation comprising a back rest pivotally mounted for swinging movement on said outer section either into a normal back supporting position or into a forward position clear of the top of said outer section and means including a link and operatively connecting said back rest with said inner section whereby swinging the back rest to forward position extends said sections from their telescoped relation and swinging the back rest to normal position retracts said sections to telescoped relation.

FRANK HOFFMAN. 60
